BUTTON LOOP

Application filed January 8, 1930. Serial No. 419,431.

This invention relates to button loops and especially to loops made from a single piece of wire having at the base of the loop substantially abutting extremities relatively secured by a coupling means permitting a limited movement.

The objects of the invention are to provide for the extremities of a button loop a tubular coupling; to provide button loop extremities of novel structure to co-operate with a tubular coupling to secure the extremities therein for a limited movement; and to provide button loop extremities with enlargements insertible within opposite open ends of a tubular coupling and means preventing their withdrawal.

The invention consists of the novel constructions, to be hereinafter described or claimed, for carrying out the above stated objects and such other objects as may herein-after appear.

The character of the invention may be best understood by reference to one illustrative device embodying the invention and illustrated by the several figures in the accompanying drawings of which the Figure 1 is a front elevation of an improved button loop in normal condition; the Figure 2 is a side elevation thereof; the Figure 3 is a front elevation with the tubular coupling illustrated in cross-section and the loop in an expanded condition; the Figure 4 is an enlarged cross-sectional face view of the tubular coupling; the Figure 5 is an enlarged cross-sectional side view of the tubular coupling; and the Figure 6 is a front elevation of a button loop of which the tubular coupling is illustrated in cross-section and in the process of assembly upon the loop extremities; the Figure 7 being a perspective view of a modified sheet metal construction of the tubular coupling in inverted position.

The device, as illustrated by the Figures 1, 2, 3, 4, 5, and 6, of the drawings, is a button loop for connecting a suspended strap to a button provided by a garment to be thereby supported, the button loop comprising a suspension loop 1, a button receiving loop 2, and a button retaining loop 3, the loops being associated in axial alignment. The button

loop is preferably formed of a single piece of resilient wire, a middle portion of which is bent to form an elongated suspension loop 1 having the horizontal bar 4, the remaining portions of the wire being co-operatingly bent to form the loops 2 and 3 having the intermediate contracted portion 5. The wire end portions are provided with aligned portions 6 parallel with the bar 4, and also the arcuate portions 7 of which the extremities are laterally provided with enlargements, each providing a key 8 extending away from but in the plane of the button loop. The tubular coupling is preferably made of the seamless tubing 9 of substantially elliptical cross-section, both ends of the tubing 1 remaining open. A depression or cut is centrally provided in a wall of the short diameter of the tubing 1 to provide the seat 10 for the shank of a button, and the opposite wall is provided with a longitudinal key-slot 11. In the formation of the associated loops 2 and 3 the contracted portion is left incomplete in the process of manufacture, as illustrated by the Figure 6, so that the portions 6 are out of alignment and not parallel with the bar 4. The wire ends are then inserted into the opposite open ends of the tubing 1 so that the keys 8 may enter the key-slot 11. The forming operation of the associated loops 2 and 3 is then completed to not only further contract the portion 5 but to also further form the shoulders 12, illustrated in full line by the Figure 6, to assume a more acute angle as illustrated in dotted line by the same figure, the completing operation lifting the portions 6 into relative alignment and in substantially parallel engagement with the inner wall surface of the tubing 1 diametrically opposite the key-slot 11 within which the keys 8 are thereby secured against dislodgment therefrom in the sliding engagement of the wire end portions within the tubular coupling, their relative movement being limited by the length of the slot 11.

In operation, the shank 13 of a button within the receiving loop 2, as illustrated by the Figure 1, may be urged through the contracted portion 5, the passage of the shank

therethrough laterally expanding the button loop from its normal condition immediately restored by the resiliency of the wire as the shank 13 passes from its position illustrated 5 by the Figure 3 to rest in the depression 10 of the tubular coupling. Upon the lateral expansion and contraction of the button loop the wire end portions readily slide within the tubular coupling upon oppositely positioned sliding bearings of which one engages 10 the inner wall surface and the other is keyed within the slot.

The modification of the structure of the tubular coupling as illustrated by the Figure 15 7 provides for the making of the tubing 9A from sheet metal centrally perforated to provide the shank-seat 10A, and provided with overlapping portions 14 and 15 both of which may be provided with a key-slot 11A, 20 the slot of one overlapping portion registering with the slot of the other portion. A tubular coupling thus made from sheet metal may be assembled upon a completely formed button loop, of the structure hereinbefore described, by being folded over the aligned portions 25 6 of the wire end portions of the button loop.

I claim:—

1. A button loop comprising a suspension 30 loop provided with a pair of depending spring arms having a contracted throat portion, the arms being divergent beyond the contracted portion and the arms extremities being bent into relative alignment, one with 35 the other, each arm extremity having an outwardly bent arcuate terminal having an enlargement providing an outwardly extending key element, and a tubular coupling having open ends to receive the said extremities including the arcuate terminals, the wall 40 of the coupling having a longitudinally extending key-slot to receive the key elements permanently retained within the slot.

2. A method of assembling and locking 45 relatively aligned portions of a button loop within a tubular coupling having open ends and a longitudinal slot, of which said portions are provided with bent extremities having key elements, for limited movement 50 within the tubular coupling, the method including the insertion within said open ends of said portions out of said alignment and the forming of said portions into said alignment while thus inserted, the key elements 55 thereby becoming inserted and locked within said slot.

3. A method of assembling and locking 60 relatively aligned portions of a button loop within a tubular coupling having open ends and a longitudinal slot, of which said portions are provided with bent extremities having key elements, for limited movement within the tubular coupling, the method including the partial forming of a throat section 65 of said loop and the insertion, within

said open ends, of said portions out of said alignment and the complete forming of said throat section while said portions are thus inserted, whereby the said portions are brought into said alignment and the key elements thereby becoming inserted and locked 70 within said slot.
